HOLDER FOR FOOD BOWL FOR PETS

Tony Robert, 5701 Southwest Freeway,
Houston, Tex. 77027

Filed Feb. 26, 1968, Ser. No. 10,710

Term of patent 14 years

U.S. Cl. D30—13
Int. Cl. D30—02

Fig. 1

The bowl shown in broken lines in FIG. 3 is depicted for purposes of illustration only.

I claim:

The ornamental design for a holder for food bowl for pets, as shown and described.
